HEEL CONSTRUCTION FOR SHOES

Osmund Teodorini, New York, N. Y., assignor of
thirty-three percent to The Granada Finance
Company Limited, Granda, British West Indies

Application June 2, 1936, Serial No. 83,009

1 Claim. (Cl. 36—36)

This invention relates to shoes, and particularly to the heel construction of shoes; and the object of the invention is to provide the heel portion of a shoe with a mounting member or adaptor of standardized form and construction in respective sizes to facilitate attachment and detachment of correspondingly standard heels; a further object being to provide a mounting member of the class described having a plurality of couplings spaced along the outer edge portions thereof and exposed through the lower surface of the member to facilitate attachment of the heel therewith, one of said couplings being of contrasting form and construction compared with the other couplings; a further object being to provide the heel portion of a shoe with a plurality of key-hole sockets forming means for detachably coupling a heel with the shoe and further with a transverse bore and socket forming additional means for retaining a heel against displacement from the shoe; a still further object being to provide a mounting or adaptor member for detachable shoe heels comprising a coupling plate imbedded in said member and exposed through the lower or outer surface thereof; and with these and other objects in view, the invention consists in a heel construction for shoes, which is constructed as more fully herein-after described and claimed.

The invention is fully disclosed in the following specification, of which the accompanying drawing forms a part, in which the separate parts of my improvement are designated by suitable reference characters in each of the views, and in which:—

Fig. 1 is a side and sectional view of a part of a shoe showing one form of construction which I employ.

Fig. 2 is a section on the line 2—2 of Fig. 1.

Fig. 3 is a view similar to Fig. 2 showing another form of construction, the section being on the line 3—3 of Fig. 4.

Fig. 4 is a section on the line 4—4 of Fig. 3.

Fig. 5 is a view similar to Figs. 2 and 3, the section being on the line 5—5 of Fig. 6; and

Fig. 6 is a section on the line 6—6 of Fig. 5.

In Fig. 1 of the drawing, I have indicated at 10 a part of the rear portion of a shoe, the heel portion 11 of which includes a heel mounting member or adaptor 12 preferably of the peripheral contour of the heel to be employed. At 13, I have shown a heel for detachable mounting with the member 12, said heel forming the subject matter of a companion application filed of 55 equal date herewith.

The member 12 may be composed of any desired material, and as shown in Figs. 1 and 2 of the drawing, this member is composed of a body of molded material in which is embodied a plurality of socket couplings 14, the inner ends of which are provided with enlarged flange portions 15 for anchoring the couplings to the member 12. The couplings 14 are provided with key-hole apertures or openings consisting of a large end portion 16 and a smaller end portion 17. The U-shaped boundary walls of the smaller opening 17 are beveled as seen at 18, note Fig. 1, so as to form a seat for the beveled or outwardly flared heads 19 of the coupling pins 20 which are imbedded in the heel 13 in the same spaced relation as the spacing of the socket couplings 14 so as to register therewith in the manner clearly illustrated in Fig. 2 of the drawing. The heads 19 of the coupling pins 20 project above the upper or inner surface of the heel 13, whereas the outer exposed surfaces of the socket couplings 14 are flush with the lower or outer surface of the member 12 as will appear from a consideration of Fig. 1 of the drawing. The member 12 may be cemented or otherwise secured to the heel portion 11 of the shoe, and if desired, nails or other fastening devices 21 may be employed to secure the member 12 in position. With large heels, three or more of the socket couplings 14 and pins 20 will be employed; whereas, with smaller heels, a lesser number of these couplings will be all that is necessary. In the operation of attaching the heel 13 to the member 12, the heads 19 of the pins 20 are first passed through the large opening 16 and the heel is moved rearwardly to bring said pins into the position shown in Figs. 1 and 2, and the interengaging beveled surfaces of the pins and socket coupling serve to draw the heel 13 snugly upon the surface of the member 12.

To retain the heel against forward movement and accidental displacement from the shoe, I employ centrally of the forward curved edge 12a of the member 12, a transverse coupling or retaining bar 22 which is imbedded in the member 12 and may also be secured to the heel portion 11 by nails or other devices 23, as indicated in Fig. 2. Rearwardly of the bar 22, the member 12 is provided with a recess 24 and the forward lower surface of the bar 22 is beveled as seen at 25 and exposed through the outer or lower surface of the member 12 to engage a projecting tongue or latch member 26 secured to the heel 13 and projecting from the upper surface of said heel. The heel 13 or that portion thereof in 55

connection with which the tongue or latch 26 is mounted will be composed of flexible material capable of being forced inwardly by a finger or fingers of the hand in order to move the tongue 26 into position to snap into the recess 24 and to engage the bar 22 in retaining the heel against displacement. To facilitate this flexing movement, the heel 13 or that part thereof immediately back of the projecting tongue 26 is recessed 10 as indicated at 27 to facilitate the flexure of the heel. In the operation of detaching the heel, the above operation is reversed, and sufficient inward pressure is applied to the heel to move the tongue 26 rearwardly, and said part of the 15 heel is forced outwardly a sufficient degree to disengage the bar 22, and the entire heel 13 is then moved inwardly to bring the pins into alignment with the large openings 16 and the heel is then disengaged by a downward movement. The 20 tongue or latch 26 forms part of a plate which is imbedded in and secured to the heel 13 as is indicated at 28.

In Figs. 3 and 4 of the drawing, I have shown a slight modification which consists simply in 25 providing a single coupling member 29 which is substituted for the independent socket couplings 14 and the coupling bar 22. The member 29 has a series of socket openings 30 similar in all respects to the sockets 14 for receiving the coupling pins 30 29 or the heads 19 thereof which form part of the heel 13. At 31, I have shown a coupling bar portion which forms a part of the front crosshead 29a of the member 29. Aside from these features, the construction and operation of the device 35 shown in Figs. 3 and 4 will be the same as that shown in Figs. 1 and 2.

In Figs. 5 and 6 of the drawing, I have shown another modification wherein a flat coupling plate 32 of substantially the same general contour as the plate 29 shown in Fig. 3 is employed. This plate may be secured directly to the heel portion 11a of the shoe or to a member 33 which takes the place of the member 12. Said member 33 has a large open socket 34 in which the coupling 32 is arranged. The lower surface of the coupling 32 is flush with the lower surface of the member 33, and if desired, a suitable filling may be employed in the large central opening 35 formed in the coupling 32, or this space may be 50 left open as is indicated in Fig. 6 of the drawing to increase the cushion properties of the heel. This type of construction will adapt itself to heels or mounting members of heels constructed 55 of leather or any other material than molded material. With the construction shown in Figs. 1 and 2, the mounting member or adaptor will be formed of rubber, rubber compositions or other suitable molded materials. It will also be apparent that with small heels such as French heels, 60 a mounting plate alone may be employed and the peripheral edges of the plate which may be exposed through the heel, may be enameled or otherwise coated to be consistent with the color-

ing of the shoe in connection with which the coupling is mounted.

With the construction shown in Figs. 5 and 6, the coupling 32 has a plurality of socket portions consisting of large openings 36 opening into smaller openings 31 forming the same key-hole construction. The walls of the smaller openings 31 are beveled as indicated at 38 in Fig. 6 of the drawing to receive the beveled or flared heads 19 of the coupling pins 20 on the heel 13. At 39, 10 I have shown the transverse coupling bar which is similar to the bar 31 and equivalent to the bar 22 shown in Figs. 1 and 2 of the drawing. The coupling 32 is recessed as seen at 40 rearwardly of the bar 39 to receive the tongue 26 of the heel 15 13. Suitable nails or other devices 41 are employed to secure the coupling 32 in position upon the heel portion of the shoe or the member 33.

With the construction shown in Figs. 5 and 6, the coupling 32 is in the form of a substantially 20 D-shaped unit, and if desired, a molded body of rubber or other material may be molded with a corresponding D-shaped recess to receive this coupling. On the other hand, if the coupling 32 is secured directly to the heel portion of the shoe, 25 the coupling may be covered with a substantially D-shaped facing and filled with a center plug substantially conforming to the contour of the opening or space 35 in said coupling.

From the foregoing, it will be understood that 30 my improved mounting member or adaptor may be manufactured and sold independently of the heel or in conjunction with the heel for application to a shoe in the repair thereof, or to a shoe manufacturer for installation directly upon the 35 shoe when made, it being understood that the spacing and arrangement of the coupling sockets in said member will be standardized as to sizes and be classified by serial numbers or other markings so as to facilitate renewal of the 40 detachable heels from time to time without the performance of any mechanical operations or shoe repairing labor, it being understood that the peripheral contour of the standardized heels and mounting members will be the same in shoes of 45 the respective sizes.

Having fully described my invention, what I claim as new and desire to secure by Letters Patent, is:—

A shoe, the heel portion of which is provided 50 with a mounting member for quick detachable mounting of a heel therewith, said member being in the form of a thin flat body of a peripheral contour corresponding to that of the shoe heel, coupling sockets imbedded in and exposed 55 through the lower surface of said member inwardly of and adjacent the outer edges thereof, other coupling means comprising a transverse bar imbedded in and exposed through the lower surface of said member inwardly of and arranged 60 adjacent the inner edge thereof, and said member having a recess registering with the entire inner surface of said bar.

OSMOND TEODORINI.
